MAURICE LUMLEY, OF CINCINNATI, OHIO, ASSIGNOR TO THE F. H. LAWSON COMPANY,
OF CINCINNATI, OHIO, A CORPORATION OF OHIO

WALL CABINET

Application filed July 1, 1929. Serial No. 375,122.

My invention relates to wall cabinets and particularly to modes of mounting such cabinets in the walls of buildings.

In the past the method of mounting sheet metal cabinets in the walls of buildings having fire proof construction has been to place a metal buck in the wall, which is in the form of a rectangular frame with a flange which is used as an abutment for the external plaster on the interior of the room, and then to set the cabinet into the frame using screws which engage in threaded bosses formed in the buck. To form these bosses a customary proceeding has been to strike out holes in the sides of the buck and grip threaded nuts about the holes or weld them in place.

The difficulty with this type of structure is that it is hard to locate the screw holes in the sides of the cabinet to register with the threaded elements in the bucks, and often an improper security of the cabinets has resulted from improper seating of the mounting screws for this reason, and furthermore, that the imbedded nuts are likely to get filled with plaster and paint.

It is the object of my invention to overcome these difficulties and provide a buck of metal to which the cabinet can be secured by means of wood screws.

I illustrate the preferred type of construction in the attached drawings, and will describe this structure in detail as being typical of my invention, the novelty of which I will set forth in the appended claim.

In the drawings:

Figure 1 is a perspective of one of the sides of a buck.

Figure 2 is a section taken through a buck with the cabinet attached therein.

Figure 3 is a front elevation of the buck by itself.

Figure 4 is a plan view of the buck.

The illustrated embodiment of my invention shows a cabinet 1 which may be of any type, and will fit within the completed buck as shown in Figure 2. The buck is formed in the customary manner of sheet metal formed into a rectangular frame having sides 2, 2, bottom 3 and top 4. The sheets are flanged outwardly at 5, and the buck is set

into the wall during the construction of the building, with the plaster 6 on the interior of the building brought in under the flanges of the buck.

Along each side wall of the buck I form attaching pads. These pads are formed of blocks of wood 6, 6, which are housed in sheet metal boxes 7, 7. The boxes fit the wood blocks snugly, and may be flanged as at 8 and welded or riveted to the inside faces of the side walls of the buck. The sheet metal boxes are formed with large holes 9, 9, therein, to provide plenty of space for mounting screws to pass through into the wood.

In mounting the cabinet it is set into the buck and wood screws 10, thrust through previously prepared holes in the cabinet and screwed into the wood. Due to the size of the holes in the pad retaining boxes, there will be no difficulty in setting the screws, and the structure will be sufficiently fire proof to withstand a fire which does not destroy a building sufficiently to render the wall fittings useless, anyhow. The metal boxes also reinforce the wood so that even if the wood would split, the cabinet would be held in place.

The placing of the pads, their size and length, and the particular mode of mounting them in place are not essential to my invention in its broader aspects.

Having thus described my invention, what I claim as new and desire to secure by Letters Patent, is:—

A mounting for a metal wall cabinet, comprising a frame with side walls intermediate the width of which metal boxes are mounted, said metal boxes retaining wooden fillers and having holes through which screws, extended through said cabinet, may be seated in said filler members.

MAURICE LUMLEY.
